UNITED STATES PATENT OFFICE.

ANTIME FONTAINE, OF NORTHAMPTON, MASSACHUSETTS.

CORNER-BRACKET.

SPECIFICATION forming part of Letters Patent No. 515,204, dated February 20, 1894.

Application filed July 28, 1893. Serial No. 481,711. (No model.)

To all whom it may concern:

Be it known that I, ANTIME FONTAINE, a citizen of the United States of America, residing at Northampton, in the county of Hampshire and State of Massachusetts, have invented 5 new and useful Improvements in Corner-Brackets, of which the following is a specification.

This invention relates to improved brackets which are more especially designed for supporting shelves at the corners of a room. Usually the horizontal supporting bracket arm has been supported with one edge thereof in contact with the wall against which the 15 shelf lies, so that the shelf is only supported at and from its end by an area corresponding to the width of the bracket arm.

The object of this invention is to devise a corner bracket for supporting the ends of 20 shelves which will have its horizontal bracket arm extended at quite a distance from the wall to and against which the back is screwed, or otherwise secured, so that the shelf may receive its support by the bracket at quite a 25 distance from the end.

In the accompanying drawings the new and improved corner bracket is shown, Figure 1 being a perspective view showing it as applied in the corner of a room for the support 30 by its bracket-arm of the shelf within its end. Fig. 2 is an elevation of the bracket,—shown as applied upon the wall,—as seen looking at the end of the bracket arm. Fig. 3 is a perspective view showing a shelf as supported 35 within an alcove at both ends by the novel brackets.

A glance at the perspective view, Fig. 1, in connection with Fig. 2, clearly indicates the form and peculiar characteristics of the 40 bracket, it being pointed out that it consists of the vertical back, *a*, to lie against the wall at, or near the corner, said back having at its

top the horizontal extension, *b*, projected in a plane at right angles to the rear bearing face of the back; this extension may be more 45 or less as desired for the offset of the bracket arm, *d*, which is a horizontal right angular continuation of the extension, *b*, so that its length is parallel with the wall against which the back is secured; the diagonal brace member, *f*, is bent or offset so that it has its extension from and between a lower part of the vertical back to the outer end portion of the bracket-arm. The back, *a*, horizontal extension, *b*, and bracket-arm, *d*, preferably have 55 the central longitudinal strengthening ribs, *g*, and the back has the screw holes, *h*, through which to secure it to the wall, while the bracket arm may also have screw holes vertically through it whereby the shelf may 60 be positively fastened thereto.

The bracket may be formed of cast iron, preferably integrally, or it may be produced in other metal or material.

Having thus described my invention, what 65 I claim, and desire to secure by Letters Patent, is—

The bracket comprising the vertical back member to have its rear face in contact with the wall, with the member, *b*, extended from 70 the top of the back member forwardly and horizontally at right angles to the said contacting rear face and continued, in the same horizontal plane, in the angularly turned support arm, *d*, which has its length alongside of, and outwardly from, the plane of said contacting rear face, and the brace member extended from a lower part of the vertical back to the forward part of the said horizontal support-arm, *d*, substantially as described. 75

ANTIME FONTAINE.
